UNITED STATES PATENT OFFICE.

FRANK R. BATCHELDER, OF WORCESTER, MASSACHUSETTS.

POCKETED CARRIER.

1,340,142.

Specification of Letters Patent.

Patented May 18, 1920.

Application filed September 25, 1918. Serial No. 255,564.

To all whom it may concern:

Be it known that I, FRANK R. BATCHELDER, a citizen of the United States, residing at Worcester, in the county of Worcester, 5 State of Massachusetts, have invented a certain new and useful Improvement in Pocketed Carriers, of which the following is a specification, reference being had therein to the accompanying drawings.

10 The invention is an improvement in pockets or receptacles of woven material, comprehended herein under the general term pocketed carriers. While primarily designed for embodiment in pocketed-carriers 15 on the order of those which are used for holding and carrying cartridges, packaged first-aid supplies, etc., the invention is applicable to pockets or receptacles in general of such material having cover-flaps in connection 20 with the mouths thereof. Among the pocketed carriers to which the invention is applicable are comprised cartridge-carriers, hospital corps belts, medical officers' belts, and others having various special adaptations.

25 One object of the invention is to avoid increase of the thickness of the pocket-walls, and undesirable bulkiness, at the places of attachment of cover-flaps in connection with 30 pockets, due to the overlapping of the shank or attaching end of a cover-flap with the wall to which the said end is attached. Other objects are indicated hereinafter.

The invention consists, essentially, in a carrier provided with an applied cover-flap, and having a wall which is woven of reduced thickness in the portion thereof upon which the attaching end of the cover-flap is overlapped, forming a kind of rabbet to receive the said attaching end, in order to avoid, as aforesaid, or materially diminish, increase of thickness and bulk as a result of such overlapping. Other features of the invention are mentioned hereinafter.

45 Illustrative embodiments of the invention are shown in the drawings, in which latter,—

Figure 1 is an isometric of a portion of a cartridge carrier containing one of the said 50 illustrative embodiments.

Fig. 2 is a view showing one of the pockets of Fig. 1 in vertical section, without cover-flaps and without contained cartridges.

Fig. 3 is a view showing in vertical section a pocket containing the other of the 55 said illustrative embodiments.

Having reference to the drawings,—

Fig. 1 shows a portion (comprising two pockets 1, 1,) of a carrier provided with a plurality of pockets, but the invention is applicable equally to carriers comprising individual pockets. By way of presenting an instance in which the result above specified secured by the invention is of especial importance, Fig. 1 shows the invention embodied in connection with pockets of a smooth-front type having rear and front cover-flaps 2, 3, which are connected respectively with the rear pocket-wall 4 and front-wall 5, respectively, and are adapted to close the pocket by overlapping with each other over the top of the pocket. The said rear and front cover-flaps are shown as furnished with fastener-members 6 and 7 of the well-known glove-fastener type, engaging with each other at the top of the pocket to fasten said cover-flaps in their overlapping closed condition, as at the right-hand side of Fig. 1. Fig. 3 shows an embodiment of the invention in connection with a pocket having a single cover-flap 2^a of the common type which is connected with the rear pocket-wall and adapted to fold forwardly over the pocket-top and fasten down in front of the pocket-front.

In accordance with the invention, the rear and front walls 4, 5, of the pockets shown in Figs. 1 and 2, and the rear wall 4 of the pocket shown in Fig. 3, have the upper portions 4^a and 5^a thereof woven thinner than the lower portions of the said walls. The shanks or attaching portions of the cover-flaps are overlapped with these thinner portions and are made fast thereto by lines 6, 6, of fastenings (usually stitches). In the drawings the combined thickness of the said thin or reduced portions 4^a, 5^a, and the said attaching portions or shanks is no greater than the thickness of the said lower portions of the pocket-walls. This has the advantage that the exposed surfaces of the said attaching portions or shanks are flush with the adjacent surfaces of the pocket-walls, which facilitates withdrawal of the pocket-contents.

Preferably, the woven construction is such that along the line where the break in thickness is located a well-defined shoulder 4^b or 5^b is formed, and in assembling the parts the ends of the shanks or attaching portions of the cover-flaps are butted against the top sides of these shoulders, so

that thereby the terminal edges of said ends are concealed and protected. This is of material importance when the said edges are raw edges, and renders unnecessary any 5 turning or folding back of the said ends to conceal raw edges, which would produce an undesirable increase of thickness. Also, the close fitting of the ends of the cover-flaps against the said shoulders avoids gaps 10 or recesses in which the contents of the pockets could catch in being inserted or withdrawn.

The shoulders 4^b and 5^b constitute stops serving as gages by which the assembling 15 and attachment of the cover-flaps in correct relations to each other in the process of manufacture are facilitated, aiding the operations and enabling the work to be performed rapidly by work-people of average 20 skill only.

The invention dispenses with housing-slits formed in the pocket-walls. For the production of pocketed carriers with such 25 slits, special procedure in the process of weaving the carriers is required. This special procedure is rendered unnecessary. When the attaching end or shank of a cover-flap is seated in a housing-slit, there are then three thicknesses of material at the 30 top of the pocket-wall, the said three thicknesses comprising the two side-walls of the housing-slit and the interposed portion of the cover-flap. It will be obvious that the combined thickness will be greater than that 35 of the two thicknesses of an overlapping joint embodying the present invention. In

the case of a smooth-front pocket of the type shown in Fig. 1, the presence of three thicknesses of material at the top of the rear wall and of three more thicknesses at the 40 top of the front wall causes the pocket to project outward at the top, and destroys the neatness of vertical appearance obtained by the present invention. With the employment of the latter, the bulk of the 45 pocket is not increased at the top.

The invention enables the cover-flaps to be attached to the pocket-walls by short overlapping end-portions, without necessitating extension of the attaching ends 50 down to the bottom of the pockets as in the case of pockets not furnished with housing-slits. It is advantageous in particular in the case of pockets woven with thick walls. The thickness of the pocket-walls and 55 cover-flap may be varied more or less.

What is claimed as the invention is:—

A pocketed carrier provided with an applied cover-flap, and having the wall on which said cover-flap is mounted woven of 60 reduced thickness in the portion upon which the attaching end-portion of the cover-flap is overlapped, and with a shoulder against which the terminal edge of said end-portion is butted.

In testimony whereof I affix my signature in presence of two witnesses.

FRANK R. BATCHELDER.
